UNITED STATES PATENT OFFICE.

BENGT M. W. HANSON, OF HARTFORD, CONNECTICUT, ASSIGNOR TO PRATT & WHITNEY COMPANY, OF HARTFORD, CONNECTICUT, A CORPORATION OF NEW JERSEY.

COMPENSATING BEARING FOR MACHINE-SPINDLES.

No. 851,005.

Specification of Letters Patent.

Patented April 23, 1907.

Application filed October 2, 1905. Serial No. 280,907.

To all whom it may concern:

Be it known that I, BENGT M. W. HANSON, a citizen of Sweden, who have declared my intention of becoming a citizen of the United States, residing at Hartford, in the county of Hartford and State of Connecticut, have invented certain new and useful Improvements in Compensating Bearings for Machine-Spindles, of which the following is a specification.

10 This invention relates to means for automatically alining machine-spindles, and more particularly those carrying tools of grinding and milling machines, in which correct position of the spindle must always be maintained in order that accurate work may be produced.

Among the several objects of the invention hereinafter set forth one of importance is the provision of improved means for so supporting the spindle that it will automatically be brought to a true position should irregularities in the running thereof exist.

A further object of the invention is the provision of means for securing the supports for the spindle after the correct alinement of the same has been effected.

In the accompanying drawings, Figure 1 is an end view of the tool-slide of a grinding-machine to which the invention is applied. Fig. 2 is a plan view of the tool-slide of a grinding-machine with the invention shown in place thereon. Fig. 3 is a horizontal section taken on line 3 3 of Fig. 1 looking in the direction of the arrow. Fig. 4 is a longitudinal vertical section on line 4 4 of Fig. 2. Fig. 5 is a side view of one of the bearing brackets or blocks of the machine, and Fig. 6 an end view of said bearing-bracket.

Like numerals designate similar parts throughout the several views.

Referring to the drawings, the numeral 1 designates the slide of a grinding or analogous machine, said slide being mounted on ways 2 of the bed 3.

45 Designated by 4 is the spindle of the machine, said spindle carrying a belt-pulley 5 and having a conical bearing 4' and a reduced and threaded extension 4''. To the end of spindle 4 is secured a hub 6, having a flange 6' on its inner side, against which is fitted the reducing-tool employed—for instance, the grinding-disk 7. This hub is chambered at 6'' for a purpose soon to be described and is

provided with a reduced cylindrical extension 6'', internally threaded at 6''' to engage the thread of the spindle and with a conical seat 6''' to fit the end 4' of said spindle. A hollow cap 8 is fitted upon the extension 6'', and the end 8' thereof bears against the tool 7. Screws 10, passing through the cap and threaded into the hub, serve to clamp the inner end of said cap against the tool and to force said tool against the flange 6', as shown in Fig. 3.

Secured to the slide 1 are brackets 12 and 13, and rising from the bases 12' 13' of said blocks are standards 12'' 13'', respectively, each standard having a tubular bearing 14, opening into an enlarged end chamber 14'. Each standard is also provided with a reinforced vertical boss 15 at one end, in which the chamber 14' is formed, with a shorter perforated vertical boss 16 rising from its base-plate at the opposite end and with a longitudinally-perforated boss 17 along its top. Depending from the base-plates of these bearing-blocks are tubular swiveling-studs 18, which are received in sockets 19 of the cross-slide. (See Fig. 6.) Passing through each bearing 14 is a swivel-bolt 20, having a reduced and externally-threaded extension 20', which engages a threaded seat 21' in the end of a bearing 22, said bearing being provided with a rabbeted journal 22', fitting into the chamber 14' aforesaid. As a pair of these bearings is illustrated and as each is alike, both are designated by the same numerals.

In each bearing 22 is formed an oil-groove 22'', fed from the usual cup 23, and fitted in each bearing is a sleeve 24, having a tapered bore, said sleeve being threaded at 24' at one end and rabbeted at 24'' at its opposite extremity. A dust-cap 25, perforated to receive the shaft 4, is fitted on the rabbeted end of the sleeve 24, and a flanged nut 26 engages the thread 24', said nut being externally threaded at 26'. Threaded upon this nut is a cap 27, internally grooved at 27', and fitted between the end of the nut 26 and the inner wall of said cap is the end flange 28' of an internally reversely tapered split box 28, as illustrated in Fig. 3. Wear or lost motion may be readily taken up by adjusting the split box by means of the nut 26 and cap mentioned, and true running con-

tact of shaft 4, passing through the pair of boxes 28, will thus be assured. Through the bases 12' and 13' and the tubular bosses 18 thereof are inserted swivel-bolts 29 29', upon which the blocks may swing in a horizontal plane, while provision is made for the swinging of the bearings 22 in a vertical plane by the turning of the bolts 20 in the bearings 14. Below the bearing 14 each block is 10 perforated at 30 and above said bearing at 30'. In the perforation 30' is a bolt 31, having a threaded end 31', adapted to engage a seat 32 in the bearing 22, and in the perforation 30 is a bolt 33, having a threaded end 33', engaging a seat 34 in the bearing 22. Each of said bolts 31 and 33 is of less diameter than the bore in which it is fitted, and consequently a slight rocking movement of each bearing 22 is permitted in the blocks 12 and 13 to enable the shaft 4 to center itself in a vertical plane. Through the tubular boss 16 of each standard a bolt 35 is passed and is threaded at its inner end into a part of the slide 1, and through the diagonally 25 opposite corner of each block 12 and 13 a bolt 36 is passed and is threaded into the bed, said bolts being of less diameter than the bores in which they are fitted to thus enable the blocks to have a slight horizontal movement around the swivel-bolts 29 29'.

At its outer end each swivel-bolt 20 is shouldered at 20° and above the shoulder is provided with a hexagonal head 20', by which it may be manipulated.

When the spindle 4 is started in rotation, all the bolts just described are loose, and an opportunity is therefore given for the spindle to center itself in correct running position. After this result has been accomplished the bolts are screwed home and all of the parts are locked firmly in place, so that there can be no movement of any of them. Should wear of the spindle take place, this is readily corrected by actuating the split sleeve 28 by means of the nut 26 and cap 27. This cap 27 also, like the cap 25, serves as a dust-guard to prevent the entrance of foreign matter to the bearing, while the chambered hub 6 serves a similar purpose in 45 surrounding the end of the cap 25.

Having thus described the invention, what I claim is—

1. The combination, with blocks having chambered standards, of bearings having ends fitted within the chambers of the standards; swivel-bolts passing through perforations of the standards, and into the bearings; a spindle; boxes carried by the bearings; and in which boxes the spindle is 55 journaled; and means for taking up wear of the boxes.

2. The combination, with blocks having standards provided with longitudinal perforations; of swivel-bolts passing through said 60 perforations; bearings connected to said

swivel-bolts; boxes mounted in the bearings; and a spindle journaled in the boxes.

3. The combination, with a support, of blocks having standards the latter provided with chambers in their ends; swivel-bolts 70 secured to the support, and passing through the bases of the blocks; bearings having journals mounted for swiveling action on the standards; boxes mounted in the bearings; and a shaft journaled in said boxes. 75

4. The combination, with a slide, of blocks each having a vertical standard provided with a series of perforations; bearings mounted on the standards, and movable with relation thereto; bolts of less diameter 80 than said perforations inserted into the bearings; a swivel-bolt located in an intermediate perforation, and also connected to each bearing; means whereby the blocks may have a limited movement in a horizontal 85 plane; and a shaft supported by the bearings.

5. The combination, with a slide, of blocks each having a vertical standard, and swiveled upon said slide; swivel-bolts mounted in perforations of the standards; bearing-boxes connected to said swivel-bolts; means for permitting limited rotary movement of the standards; sleeves inserted in said bearings, and having tapered bores; split, externally-tapered boxes flanged at their inner ends, and fitted in the sleeves; means for taking up wear of said split boxes; and a shaft journaled in the split boxes. 95

6. The combination, with a slide, of blocks swiveled upon said slide, and each having a series of bores; means for locking said blocks against swiveling action on the slides; bearings having tubular bosses fitted in chambers of the standards; bolts of less 105 diameter than the perforations through which they are passed for securing the bearings to the standard; swivel-bolts passed through the intermediate perforations of the standards, and threaded into the tubular 110 bosses of the bearings; sleeves carried by the bearings, and each having an internally-tapered wall; split boxes with externally-tapered peripheries fitted in said sleeves; a shaft journaled in said boxes; and means for adjusting the boxes to take up wear. 115

7. The combination, with a bearing, and with means whereby it may be universally adjusted, of a sleeve inserted in said bearing, and having an internally-tapered wall, said 120 sleeve being provided with a rabbet at one end, and with an external thread at its opposite extremity; a nut in engagement with the threaded end of the sleeve, and having an external thread; a cap threaded upon 125 said nut; a split box having a flange at one end, said flange being located between the end of the nut, and the inner wall of the cap threaded upon said nut; and a shaft passing through the split box. 130

8. The combination, with a slide, of blocks provided with perforated standards, and with flat bases secured to said slide, each of said bases having perforations; bolts of less diameter than said perforations, said bolts being connected to the slide; a swivel-bolt passing through each base, and entering the slide; bearings; swivel-bolts connecting the bearings and standards; bolts of less diameter than the perforations in the stand-

ards; means for locking the bearings to said standards; and a spindle journaled in the bearings.

In testimony whereof I affix my signature in presence of two witnesses.
